[57] CLAIM

The ornamental design for a floppy beret with elastic headband, as shown and described.

DESCRIPTION

FIG. 1 is a front perspective view of a floppy beret with elastic headband showing my new design;

FIG. 2 is a top plan view thereof;

FIG. 3 is a elevational view thereof, the opposite side being a mirror image thereof;

FIG. 4 is a bottom plan view thereof;

FIG. 5 is a front perspective view in an alternate position; and,

FIG. 6 is a front perspective view in an alternate position.

The broken line showing of the person's face is for illustrative purposes only and forms no part of the claimed design.

FIG. 1.**FIG. 2.****FIG. 3.**

FIG. 4.**FIG. 5.****FIG. 6.**
